UNITED STATES PATENT OFFICE.

JAMES A. COGSWELL, OF BOSTON, MASSACHUSETTS.

PAVING-BLOCK.

1,068,739.

Specification of Letters Patent.

Patented July 29, 1913.

Application filed May 25, 1912. Serial No. 699,615.

To all whom it may concern:

Be it known that I, JAMES A. COGSWELL, a citizen of the United States, residing at Boston, in the county of Suffolk and State 5 of Massachusetts, have invented an Improvement in Paving-Blocks, of which the following is a specification.

This application is a continuation of my application #595,548, filed December 5, 10 1910.

This invention relates to paving-blocks, and has for its object to provide a wooden paving block with an improved form of metallic plate or grid adapted to be inserted in 15 a recess in the block and to be securely held in said recess.

Figure 1 is a perspective view of several paving blocks embodying this invention, arranged to form a street paving. Fig. 2 is a 20 vertical section of the block taken on the dotted line 2—2, Fig. 3. Fig. 3 is a side elevation of the block. Fig. 4 is a side elevation of the block, illustrating one method of driving in the metallic plate. Fig. 5 is a 25 vertical, longitudinal section of the block, showing the securing means for the plate. Fig. 6 is an end view of a block with a modified form of metallic plate. Fig. 7 is a side view of the block shown in Fig. 6, showing 30 the method of driving in the metallic plate. Fig. 8 is a side view of another modified form of plate, Fig. 9 is a vertical section of the plate shown in Fig. 8, taken on the dotted line 9—9. Fig. 10 is a side view of an 35 other modified form of plate. Fig. 11 is a vertical section of the plate shown in Fig. 10, taken on the dotted line 10—10. Fig. 12 is an end view of a plate similar to Fig. 10, 40 having a projection on one side only.

a represents a block, which is made of 45 wood and of any usual or suitable shape and dimensions. It may be treated with a preservation, if desired. It has a saw cut or kerf *a'* in its upper side or face extended from end to end of it and usually arranged intermediate its width.

b represents a plate of iron, steel or other 50 suitable metal. It is made of a thickness corresponding to the width of the saw cut or kerf in the block, so that it may be driven into said kerf, and is made of a length corresponding to the length of the block or thereabout, and is made of a width slightly greater than the depth of the kerf, so that 55 when driven thereinto and bottoming there-

in it will project slightly beyond the face of the block. For the purpose of holding said metallic plate in the kerf in the block it is provided with one or more spurs or projections arranged on one or both sides of 60 it, which have groove-forming portions whereby they are adapted to cut their way into the side wall of the kerf when the plate is forcibly driven thereinto, thereby to occupy a position beneath uncut portions of 65 said side wall. In Figs. 1 to 5 said plate is provided on both of its sides with spurs *b'*, arranged in rows which are extended lengthwise the plate, although they may be otherwise arranged, and on one side only 70 of the plate. Said spurs project outwardly short distances.

In lieu of providing the plate with numerous spurs *b'*, as a securing means, a modified embodiment of my invention is shown in 75 Figs. 6 and 7, wherein *c* represents the metallic plate which is provided on one or both sides with a long rib *c'* extended longitudinally, from end to end thereof or thereabout, and made chisel pointed at the ends. Or, 80 in lieu thereof, the plate may have on one or both sides of it one or more short ribs, as represented at *d*, Figs. 8 and 9, formed with flat tops and inclined sides. Or, in lieu thereof, said plate may have formed on 85 one or both sides of it long ribs *e* extended longitudinally from end to end of it at the bottom, said ribs having flat bottoms flush with the bottom of the plate and having inclined tops, as represented in Figs. 10, 11 90 and 12. This latter form, in addition to cutting its way into the side wall of the kerf when the plate is forcibly driven thereinto, also increases the area of the bottom 95 of the plate, which is an advantage.

When driving the plate of Figs. 1 to 5 into the kerf the spurs *b'* cut their way and form tracks or ways along the side walls of the kerf, but such tracks or ways will permit of the easy removal of the plate, and 100 as it is designed and intended to arrange the spurs or ribs beneath uncut portions of the side walls, the plate will be driven into the kerf in the block while deposited a little at one side of the block, as shown in Fig. 4, 105 after which it is forcibly thrust endwise a short distance, until the ends thereof are flush with the ends of the blocks or thereabout. When driving the plates of Figs. 6 to 12 into the kerf they will be driven end- 110

wise, as represented in Fig. 7, instead of transversely and then endwise, as represented in Figs. 1 to 5. In all instances, however, the spurs, projections or ribs are shown, 5 which are adapted to cut their way along the side wall of the kerf, and to occupy positions beneath uncut portions thereof, in view of being equivalents, may be and herein are termed "projections."

10 I claim:—

1. A paving-block of wood having a kerf extended from end to end of it, intermediate its width, and a metallic plate arranged to bottom in said kerf and to project slightly therefrom, said plate having one or more outwardly extended projections arranged on its sides, and said projections having groove-forming portions, substantially as described.

2. The paving-block herein described having a kerf extended from end to end of it, 20 and a metallic plate arranged to bottom in said kerf and to project slightly therefrom, said plate having one or more projections arranged on its sides at the bottom and extended from end to end of it, said projections having groove-forming portions and the bottoms of said projections being flush with the bottom of the plate.

In testimony whereof, I have signed my name to this specification, in the presence of 30 two subscribing witnesses.

JAMES A. COGSWELL.
